UNITED STATES PATENT OFFICE.

ALBERT N. PORTER, OF TULSA, OKLAHOMA.

TARGET.

Application filed May 5, 1923. Serial No. 637,016.

To all whom it may concern:

Be it known that I, ALBERT N. PORTER, a citizen of the United States, residing at Tulsa, in the county of Tulsa and State 5 of Oklahoma, have invented certain new and useful Improvements in Targets, of which the following is a specification.

This invention relates to targets and it consists in the novel features hereinafter 10 described and claimed.

The object of the invention is to provide a target with an audible alarm signal mounted upon the field of the target and which is located in the path of movement 15 of a figure, also movably mounted upon the field, and susceptible of being struck by the figure, when the figure is hit and moved by a bullet or other missile. The figure simulates a bird in outline and therefore the 20 target structure is known as a flying bird target.

A further object of the invention is to provide means for directing or guiding the figure toward the alarm when the figure is 25 hit and moved and for returning the figure to its normal position at the center of the field of the target. Means are provided for protecting the guiding means from the shot.

30 A still further object of the invention is to provide means whereby the figure may be visible as an eye or mark to the marksman irrespective of the side of the field which is presented to view so that the minor features or parts of the target structure may 35 be shielded behind the field when a high power rifle is used for shooting at the target. Therefore the field is provided with a central opening opposite which the figure is normally disposed and the edges of the 40 said opening frame or surround the outline of the figure.

In the accompanying drawings—

45 Figure 1 is a front elevational view of the target structure.

Figure 2 is a similar view looking at the opposite side thereof.

Figure 3 is an edge view of the target.

50 Figure 4 is a fragmentary vertical sectional view.

As illustrated in the accompanying drawings the target structure comprises a circular field member 1 which is provided around its edge portion with a strip 2. The field is provided at its center with an opening 3 which is preferably elliptical in shape.

A bracket 4 is mounted at the upper portion of the field and at one side thereof and carries a bell or gong 5. A bracket 6 is mounted upon the intermediate portion of the field at one side of the opening 3 and a vertically disposed spiral member 7 is mounted upon said bracket. An arm 8 is provided at a point between its ends with an opening 9 which receives the spiral member 7 and the arm is provided at the opposite sides of the opening therein with lugs 10 which lie between the convolutions of the spiral member 7. The said arm normally rests upon the upper surface of the bracket 6. A figure 11 is carried at one end of the arm 8 and normally lies opposite the opening 3 in the field of the target and approximately at the center thereof and serves as the eye or mark of the target structure. 75 A counter-balance weight 12 is carried at the other end of the arm 8.

A tube 13 is mounted upon the intermediate portion of the arm 8 and surrounds the opening 9 therein and encloses the spiral member 7 and serves as a shield for the same. A guide bracket 14 is mounted at the upper portion of the field and loosely receives the upper portion of the tube 13 so that the said tube is free to rotate and move 80 vertically in the last mentioned bracket. The bell or gong 5 is located in the path of movement of the figure 11. The field 1 is provided with an opening 15 which is located in vertical alinement with the center 85 of gravity of the target structure whereby the said structure will hang vertically when the field is supported by a nail or other object passed through the opening 15.

When the marksman is using a low power rifle or rifle of small calibre the side of the field 1 at which the gong the tube and the figure are mounted is exposed to the marksman. When a high power rifle is being used the opposite side of the field is exposed and 100 the body of the shield protects the tube, arm and gong from injury from the shot. When the side of the field at which the said parts are mounted is exposed to the marksman the tube 13 protects the spiral member 105 7 from the shot. The field 1, preferably, is provided with a white surface and the eye or figure 11 is preferably painted black so that there is a distinct contrast between the field and bull's eye of the target structure. 110

By reference to Figure 4 of the drawing it will be seen that the spiral member 7 is of

greater length than the distance between the brackets 6 and 14. Either end of the spiral member 7 will fit frictionally in the opening in the bracket 6. Therefore when the target field is turned around the spiral member 7 is inverted in its position in the brackets so that the spirals will be disposed to cause the figure to move in an upward direction toward the bell when a hit is made.

19 When the figure 11 is struck by a shot it is rotated about the axis of the spiral member 7 and carries the arm 8 around with it. Thus the lugs 10 are moved along the convolutions of the spiral member 7 and the 15 arm 8 moves upwardly along the spiral member carrying the figure and tube 13 with it.

20 The tube 13 is guided in the bracket 14 so that the figure 11 will strike the bell or gong 5 and thus an audible sound or signal is given which signifies that the marksman has made a bull's eye shot or rung the target. Also the movement of the figure 11 will 25 visibly indicate that such a shot or hit has been made.

When the figure 11 strikes the bell the upward and turning movements of the figure, tube and arm are checked and the said parts for the moment come to a state of rest. 30 The parts then descend by gravity to their normal positions and the target structure is set for the next shot.

Having described the invention, what is claimed is:—

35 1. A target comprising a field, a signal alarm mounted thereon, a figure mounted for movement over the field and located below the alarm and serving as the eye of the target and means for guiding the figure in an upward direction toward the alarm when the figure is struck by a missile.

2. A target comprising a field, a signal alarm mounted thereon, a figure mounted for movement over the field and located below the alarm and serving as the eye of the target and means for guiding the figure toward the alarm when the figure is struck by a missile and gravity means for returning the figure to its normal position after it strikes the alarm.

3. A target comprising a field, a signal alarm mounted thereon, a spiral member mounted thereon, an arm having lugs which engage between the convolutions of the spiral member and a figure mounted upon 55 the arm and serving as the eye of the target.

4. A target comprising a field, a signal alarm mounted thereon, a spiral member mounted thereon, an arm having lugs which engage between the convolutions of the spiral member, a counterbalance weight carried at one end of the arm and a figure mounted upon the other end of the arm and serving as the eye of the target.

5. A target comprising a field, a signal alarm mounted thereon, a spiral member mounted thereon, an arm having lugs which engage between the convolutions of the spiral member, a tube carried by the arm and normally enclosing the spiral member 70 and a figure mounted upon the arm and serving as the eye of the target.

6. A target comprising a field having an opening, a signal alarm mounted upon the field, a figure mounted for movement over the field and serving as the eye of the target and normally disposed opposite the opening in the field and means for guiding the figure toward the alarm when the figure is struck by a missile.

In testimony whereof I affix my signature.
ALBERT N. PORTER.
